UNITED STATES PATENT OFFICE.

SYDNEY STARKEY, OF EAST LIVERPOOL, OHIO.

DESIGN FOR A JUG.

SPECIFICATION forming part of Design No. 29,468, dated October 11, 1898.

Application filed May 21, 1898. Serial No. 681,381. Term of patent 3½ years.

To all whom it may concern:

Be it known that I, SYDNEY STARKEY, a citizen of the United States, residing at East Liverpool, in the county of Columbiana and State of Ohio, have invented and produced a new and original Design for Jugs; and I do hereby declare the following to be a full, clear, and exact description of the invention, such as will enable others skilled in the art to which it applies to make and use the same, reference being had to the accompanying drawing, forming a part of this specification.

This invention relates to designs for jugs; and it consists of the essential features as 5 hereinafter more fully set forth.

The accompanying drawing represents a perspective view of a jug embodying the design.

The sides A and B of the hollow body are 5 parallel with each other and the edges *a b* arranged in planes at right angles to the planes of the said sides and tapered from a horizontal line a short distance below the top to the bottom *c*. The top portion C is made somewhat narrower than the portion below it, and its edges *d e* are tapered from the top downward and inward to the shoulders *f g*, the lat-

ter extending outwardly and downwardly to unite with the edges *a b*.

The shape of the device as thus far described is old and of the form of the well-known keystone.

The essential features of the design reside in a handle *f'*, which curves outwardly and downwardly from the upper portion of one edge *e* of the top C and meets an inclined straight portion *f''*, merging into the outer termination of the shoulder *g*. Also projecting vertically from the end of the upper edge of the top C, opposite to that to which the handle is connected, is a circular hollow neck *h*, having a flaring top flange *i*. The part of the neck below the flange is curved regularly and merges into the adjacent part of the top C.

Having thus described the invention, what 45 is claimed as new is—

The design for a jug as herein shown and described.

In testimony whereof I affix my signature in presence of two witnesses.

SYDNEY STARKEY.
